UNITED STATES PATENT OFFICE.

WILLIAM C. F. ZIMMERMAN, OF LONE TREE, IOWA.

CABLE TAKE-UP.

1,245,854.

Specification of Letters Patent.

Patented Nov. 6, 1917.

Application filed October 17, 1913. Serial No. 795,712.

To all whom it may concern:

Be it known that I, WILLIAM C. F. ZIMMERMAN, a citizen of the United States, residing at Lone Tree, in the county of Johnson and State of Iowa, have invented certain new and useful Improvements in Cable Take-Ups; and I do hereby declare the following to be a full, clear, and exact description of the invention, such as will enable others skilled in the art to which it appertains to make and use the same.

This invention relates to improvements in cable take-ups, and particularly to devices of this character provided with a cam cable grip, such, for instance, as indicated in my prior Patent No. 615,945, dated Dec. 13, 1898.

Although the structure illustrated in said patent has proved very efficient, certain difficulties in its use have manifested themselves, one of which is the tendency toward interference between the loose ends of the cable and the crossing taut portion of the cable, no particular provision being made for locating the loose end out of the path of the taut portion with the result that some times in practice the crossing portions of the cable are injured and some times the flange of the pulley is spread or broken. Another difficulty some times arising in the use of the said patented take-up is a tendency on the part of the taut portion of the cable to slip below the main plate of the take-up, and a still further objection arises from the use of the return lap of the short cable, because of the incident waste of cable.

The objects of the several features of improvement are to effectively overcome these difficulties as will in part be hereinafter pointed out and in part become apparent.

In the accompanying drawing,—

Figure 1 is a plan view of a take-up embodying the features of the present invention.

Fig. 2 is a front view thereof.

Fig. 3 is a vertical section taken on the planes indicated by line 3—3 of Fig. 1 and looking in the direction indicated by the arrow.

Referring to the drawing by numerals, 1 indicates the main plate which is strengthened by appropriate ribs or flanges 2, 2, at its under face, and is provided with a transverse, arcuate flange 3 upstanding from its upper face, the flange 3 being strengthened by lateral flanges or ribs 4, 4. All of said

flanges are preferably formed integral with plate 1, the said plate and connected parts being preferably a casting but obviously capable of other construction. A downwardly opening hook 5 outstands laterally from and is disposed above plate 1 and preferably formed integral therewith, the hook 5 being disposed at one end of the plate and extending from one edge thereof, while the cable 6 guiding and retaining lug 7 is formed integral with the same edge of the plate but is disposed at substantially the opposite end thereof and outstands laterally therefrom. The plate 1 is formed with a longitudinal bore 8 enlarged as at 9 throughout a portion of its length, the short or hitching cable 10 being disposed with its end portion extending through the bore 8, the cable being of a diameter filling the bore except at the 75 enlarged portion 9, whereat the strands of the cable are spread apart and crimped and interfilled with babbitt or other appropriate material, as indicated at 11. The opposite end of the hitching cable 10 is connected to 80 a cable hook 12 adapted to facilitate application of the cable.

The major portion of the upper face of plate 1 is flat and smooth, and an eccentric disk or cam 13 rests flatwise thereon, a stud 14 upstanding from the upper face of plate 1 and forming a bearing for disk cam 13, said disk cam being formed with an aperture surrounding said stud and disposed eccentric to the circle described by the periphery of the disk, so that the disk acts as a cam in revolving on the stud 14 as a pivot. A cross pin 15 extends through stud 14 above cam 13 so as to obviate the possibility of accidental dislocation of the cam. 95 The face of flange 3 next the cam 13 is curved to conform to the periphery of the cam, and the eccentric mounting of the cam is such as to cause any object interposed between the cam and flange to be firmly 100 gripped and clamped therebetween. Cam 13 is formed with a circumferential, peripheral cable-receiving groove 16, providing cable-retaining flanges which are continuous except for an interruption of the upper 105 flange by a branch-groove 17 disposed adjacent the flange 3 when the cam is in its gripping position. The branch groove 17 is formed by the provision of an extra wide flange 18 extending from cam 13 and serving to confine the loose end of the draft cable 19 to sustain the same out of con-

tact with the taut portion of the cable. Branch 17 leads spirally from the groove 16 so that the cable 19 naturally accommodates itself to the position given it in said 5 grooves incident to a wrapping of the cable about the cam.

In operation, when it is desired to hitch some intermediate point of draft cable 19 to an object, as for instance, a stump to be 10 pulled, it is not necessary to wind in the full length of draft cable, but instead, an embodiment of the present invention is applied to the desired point of the draft cable by merely swinging the cam 13 on its pivot 15 outwardly to the position indicated in dotted lines in Fig. 1, coiling a single coil of the cable 19 about the cam with the loose end extending along the branch groove 17 while the main portion of the coil lies in the 20 groove 16, and the draft cable extending through hook 5, and then swinging the cam into the clamping position seen in Fig. 1. It will, of course, be obvious that the loose 25 end of the cable extending out of groove 17, while shown in the drawing only as a stub for the saving of space, may in fact be a hundred feet long or of any other length, according to how much of the draft cable 30 has been paid out, and the relative location of the point of application of the cam hitch. When the cam hitch has thus been applied to the draft cable, the hitch cable 10 may be applied appropriately to the object to be drawn. To detach the hitch cable to the 35 draft cable, it is only necessary to relax the stress on the draft cable, swinging disk cam 13 to the dotted line position of Fig. 1, and recoil the draft cable from the cam. Obviously, flange 3 may be any appropriate stop 40 or shoulder coöperating with cam 13 to clamp the cable. Retaining lug 7, in practice, effectively prevents accidental slipping of the draft cable below the plate or body 1.

Owing to the extraordinarily heavy strain 45 to which the parts are subjected, the flange 3 and cam 13 are so disposed with relation to each other as to obviate the possibility of the cam swinging to a position sufficiently beyond the dead center line to wedge between 50 its pivot 14 and the flange 3. In fact, the position of these parts is such that the cable will be gripped only while under pressure, that is while the pulling cable is subjected 55 to strain and when this strain is relieved the cam 13 is free to swing laterally to the dotted line position for enabling removal of the take-up from the cable 19. Thus any such disastrous results as would follow wedging of the cam against the cable while 60 the cable is disposed between the cam and flange 3 are avoided.

While I have illustrated but a single cable 10 it is apparent, of course, that the plate 1 may be provided with a cluster of such cables in any appropriate number, such as 65 16 would enable the connection of the pulling cable 19 to a plurality of stumps at one time. The multiple number of cables 10 would, of course, be varied according to conditions and could all be secured in the bore 70 8 or when preferred the plate 1 could be provided with a number of bores 8 corresponding to the number of cables 10 of the cluster.

What I claim is:—

1. In a cable take-up, the combination of a body plate provided at one side with spaced apart longitudinally extending integral reinforcing ribs and having on its opposite side near one end a transversely 80 extending stop flange curved inwardly at one end and provided with outstanding integral reinforcing flanges at its outer side merging into the body plate, said body plate being provided near one lateral edge with a longitudinally extending cable receiving 85 socket enlarged at one end to receive the unraveled extremity of a cable to bind the latter in the socket, and a disk eccentrically mounted upon the said flat opposite side of the body plate and adapted to swing into engagement with the curved end of said stop flange to bind between the disk and the flange a cable wound upon the periphery of 90 the disk, said disk having a grooved projection at one side thereof into which the cable is adapted to be trained to prevent overlapping of the cable on the disk.

2. In a cable take-up, the combination of a body plate provided with a flat side and a stop flange rising from one end of the plate at said side, and a disk eccentrically pivoted to the body plate against said flat side and provided with a peripheral groove adapted to receive a cable therein, said disk having 100 a projection upon its side opposite from the plate, and the projection having a groove 105 therein leaning obliquely from the peripheral groove of the disk to receive a portion of the cable wound upon the disk, said projection and groove therein being located at a point diametrically opposite to the eccentrically pivoted point of the disk to prevent overlapping of the cable wound upon the disk.

In testimony whereof I affix my signature in presence of two witnesses.

WILLIAM C. F. ZIMMERMAN.
